UNITED STATES PATENT OFFICE.

JOHN T. BEECHLYN, OF LYNN, MASSACHUSETTS, ASSIGNOR TO GENERAL ELECTRIC COMPANY, A CORPORATION OF NEW YORK.

COIN-CONTROLLED APPARATUS.

1,176,642.

Specification of Letters Patent. Patented Mar. 21, 1916.

Application filed November 4, 1912. Serial No. 729,254.

To all whom it may concern:

Be it known that I, JOHN T. BEECHLYN, a citizen of the United States, residing at Lynn, county of Essex, State of Massachusetts, have invented certain new and useful Improvements in Coin-Controlled Apparatus, of which the following is a specification.

The present invention relates to coin controlled mechanism and more especially to coin controlled mechanism adapted for use in connection with power devices, whereby the latter may be started on the insertion of a coin, and automatically stopped after a predetermined amount of work has been performed.

The object of the invention is to provide an improved device of this character which shall be of compact and hardy construction, positive in operation, and of low cost to manufacture.

My invention is adapted for use in connection with a variety of power devices, although for the purposes of this application, I have shown and described it in connection with an ordinary fan motor only.

Referring to the accompanying drawing Figure 1 is a plan view with parts in section of my coin controlled device; Fig. 2 is a vertical section thereof; Fig. 3 is a detached plan of certain parts in different relation to that occupied by them in Fig. 1; Fig. 4 is a side elevation of a fan motor with my coin controlled apparatus applied thereto; and Fig. 5 is an enlarged view showing the relation of the crown escape- 35 ment pawl to the ratchet disk.

The frame of the device consists of a cast metal box 1, which may be an integral extension of the motor casing, having a cover 2, and at one side a recess for telescopically receiving the coin box 3 which is provided with ears 4 opposite an ear 5 at the lower end of the box 1 for the reception of a locking device 6 in the form of a padlock. The rear end of the armature shaft 7 of the motor has a worm 8 thereon in mesh with a worm wheel 9 on a shaft 10 supported in bearings 11 and 12 in opposite ends of a sheet metal frame 13 secured to the back of the box 1 by screws 14. The shaft 10 is provided with a worm 15 which meshes with a second worm wheel 16 on a shaft 17 also journaled in the frame 13 but at right

angles to the shaft 10. On the shaft 17 is 55 a worm 18 which meshes with a third worm wheel 19 mounted on an axially movable shaft 20. At the inner end of the shaft 20 is a head 21 formed into a crown escape- 60 ment pawl having a single notch 22 and designed to engage a ratchet disk 41 to be hereinafter referred to. The shaft 20 is provided with a helical spring 23 operating to yieldingly hold the crown pawl in engagement with its ratchet disk. It will thus 65 be seen that the crown pawl is so connected through the train of gears to the armature shaft of the motor as to make one revolution for every hundred thousand or other- 70 number of revolutions of the motor shaft, according to the ratio of the gear train.

When my device is used to control an electric motor, I arrange to make and break the electric circuit, and this is accomplished in the device shown in the drawings 75 by a circuit interrupter in the form of electric contacts 24 and 25, consisting of platinum tipped spring arms secured through insulation 26 to the front end of the sheet metal frame 13 and having provisions at 80 27 for connecting to the severed ends of a conductor wire of the motor, so that when the contacts 24 and 25 are separated the circuit through the motor will be broken, and closed when they are brought together. 85 To enable these contacts to be operated, they are each provided near its free end with an insulating block 28 carrying a vertical peg 29.

The mechanism for controlling the admission and deposit of a coin consists of a coin chute in the form of a flattened sheet metal bushing 30, having an opening to fit the coin designed to be used, and extended through the cover 2 of the frame near one 95 edge thereof. The lower outer edge of the bushing 30 is provided with a horizontal ledge 31 for preventing a coin of the right size from dropping through until it has been moved to the rear end 32 of the ledge. 100 The rear wall of the bushing is cut away on the arc of a circle, as indicated by dotted line 33, Fig. 2, so that when the coin 34 rests upon the ledge 31 it may readily pass transversely out of the chute. Directly beneath the bushing 30, an opening 36 is made in the floor of the box, so that a coin may drop freely into the receptacle 3,

and in order to prevent a coin from lodging beyond the opening 36 a vertical partition 37 is located at the rear side thereof.

The means for controlling the position of a coin and setting the device in operation consists of a hand knob 38 having a shaft 39 extending vertically through a bearing in the cover 2 and carrying at its inner end a sheet metal plate 40 rigidly fixed thereon and a sheet metal ratchet disk 41 loosely journaled thereon. The cam plate 40 has approximately 180 degrees of its periphery of short radius, so that it will not interfere with the crown pawl 21. About 90 degrees of the remaining periphery is at a longer radius and extends into a transverse slot cut in an edge of the bushing 30 so that a proper sized coin 34 will normally be prevented from passing, as indicated in full lines in Fig. 2. The remaining portion of the periphery is made irregular to form a cam 42 adapted to engage the stud 29 of contact 25 when moved into the position shown in Fig. 3, and its leading end is cut off abruptly on a radius and extended into a notch 43 sufficiently deep to permit a coin to pass freely through when it is brought adjacent the bushing 30. The ratchet disk 41 is provided with a plurality of coin slots 44 and directly opposite thereto with ratchet teeth 45 having a spacing approximately two-thirds the diameter of the crown pawl 21, and between the series of coin slots 44 and the series of teeth 45 it is provided with a recess and cam 46 adapted to engage the peg 29 of contact 24. The plate 40 is biased counter-clockwise by a spring 47 connected to the left hand side of the box 1 and to a pin 48 projecting upwardly from the plate, and ratchet disk 41 is correspondingly biased by a spring 49 connected to the box and to a pin 50 extending upwardly from the disk, and through an arced slot 51 in the plate 40. The knob 38 is provided with two stop pins 51, 52 adapted to engage a stop peg 53 projecting upwardly from the upper surface of the box cover 2.

With the parts in the position indicated in Fig. 1 and upon inserting a coin in the bushing 30 it will rest upon the larger circular periphery of the cam plate 40, then turning the knob 38 clockwise, the cam plate 40 moves forward until the notch at 43 permits the coin 34 to descend until arrested by the detector ledge 31 where it is arrested directly opposite ratchet disk 41 and in a slot 44 thereof, and upon a continued movement of the knob, the radial shoulder 54 of the plate engages the side of the coin, as shown in Fig. 3, so that the coin then operates as a locking means between the plate 40 and ratchet disk 41, and upon still further movement of the knob 38 the ratchet disk is moved the distance of one ratchet tooth 45 pushing back the crown

pawl 21 until it slips over and engages a ratchet tooth 45. As the cam plate 40, through its coin connection with the ratchet disk 41, moves the latter, the contact 25 is forced outwardly by the cam 42 sufficiently far to prevent engagement therewith by the contact 24, although the latter is also moved from its innermost position to its normal operating position by the cam 46 of the ratchet disk, as indicated in Fig. 3, so that the motor circuit is not completed until the cam plate has been allowed to move backwardly sufficiently to withdraw its cam 42 from engagement with the contact 25. This necessarily effects a release on the coin which drops into the receptacle 3. This retractive movement of the cam plate prior to the closing of the electric circuit prevents the fraudulent withdrawal of a coin or slug. Any number of coins up to five in the device shown may be inserted in sequence at one time, each enabling the ratchet disk to be moved forward one tooth, and the coin slots 44 are positioned relative to the ratchet teeth 45 to permit such series of insertions. It will be noted, however, that the coin slots 44 are twice as frequent in spacing as the teeth 45, and this is for the purpose of enabling a coin to be inserted whether the crown pawl be in a position to engage a ratchet tooth on its outer periphery, as shown in Fig. 2, or on its opposite inner periphery, as shown in Fig. 3. When the pawl engages the ratchet teeth on its outer periphery, the coins will enter the odd numbered slots, and when in the position, shown in Fig. 3, the coins will enter the even numbered slots. Upon retraction of the cam plate to the position shown in Fig. 1 and with the ratchet disk advanced as shown in Fig. 3, the contacts 24, 25 will be in engagement and the electric circuit completed through the motor. The crown pawl 21 is constantly rotated at a mere fraction of the speed of the motor shaft and its slot 22 finally brought opposite a ratchet tooth, so that the ratchet disk escapes under the tension of its spring 49, half a tooth space, where it is arrested by a tooth 45 coming in contact with the inner periphery of the crown, as shown in Fig. 5, and upon completion of the revolution of the crown pawl, the ratchet disk is again released for half a tooth space. In case but one coin has been inserted, this second half step brings the ratchet plate to the position shown in Fig. 1 with the peg 29 of contact 24 resting in the slot 46 and the contacts separated, but in case several coins have been inserted the crown pawl will make an equal number of revolutions before contact 24 is freed.

I do not desire to restrict myself to the particular form or arrangement of parts herein shown and described, since it is apparent that they may be changed or moved without departing from the invention.

What I claim as new and desire to secure by Letters Patent of the United States is:—

1. In a prepayment motor the combination of a manually operated plate, a ratchet disk parallel to said plate, said plate and disk having provisions whereby they may be locked together by a coin, a motor circuit interrupter in operative engagement with said ratchet disk, and an escapement pawl for said disk directly actuated by the motor.
2. In a prepayment motor, the combination of a rotary plate biased to turn in one direction, a ratchet disk parallel to said plate, said disk and plate having provisions whereby they may be locked together by a coin, a motor circuit interrupter in operative engagement with said disk and said plate, and an escapement pawl for normally holding said disk, actuated by the motor to release the same.
3. In a prepayment motor, the combination of a rotary plate, a ratchet disk adjacent said plate, said plate and disk having provisions whereby they may be locked together by a coin, a motor circuit interrupter comprising coöperating parts actuated respectively by said plate and said disk to effect closure of the circuit, and an escapement pawl for normally holding said disk, actuated by the motor to release the same.
4. In a prepayment motor, the combination of a rotary plate provided with a peripheral notch, a ratchet disk biased to turn in one direction provided with a cam and one or more coin slots, means for introducing a coin into a slot of said disk, a circuit interrupter in engagement with the periphery of said disk, and an escapement pawl for normally holding said disk from backward movement actuated, by the motor to release said disk.
5. In a prepayment motor, the combination of a manually operated plate, a disk parallel to said plate biased to move in one direction and provided with ratchet teeth, said plate and said disk having provisions whereby they may be locked together by a coin, a circuit interrupter in operative engagement with said disk, and an axially yielding crown escapement pawl engaging said ratchet teeth and directly and continuously rotated by the motor.
6. In a prepayment motor the combination of a manually operated plate, a disk parallel to said plate and provided with spaced ratchet teeth, said plate biased to move in one direction and said disk having provisions whereby they may be locked to-

gether by a coin, a circuit interrupter in operative engagement with said disk and a crown escapement pawl for said disk having a diameter approximately one and a half times the spacing of said ratchet teeth and rotated by the motor.

65

7. In a coin controlled device, the combination of a coin chute, a detector ledge located adjacent said chute, a plate rotatably intersecting said chute, a power controlling disk parallel to said plate biased to turn in one direction, and provisions whereby a coin may lock said plate to said disk until said coin is moved beyond said ledge, and for preventing the turning on of power until said coin has thereafter been released by reverse movement of said plate.

8. In a coin controlled device, the combination of a coin chute, a detector ledge located transversely at the inner end of said chute, a plate rotatably intersecting said chute and provided with a coin engaging shoulder, a power controlling disk parallel to said plate and provided with one or more coin slots, and means for preventing the turning on of power until the coin has been moved beyond said ledge by said plate and the latter returned across said chute.

9. In a coin controlled device, the combination of a coin chute, a detector ledge located adjacent said chute, a rotary plate having a peripheral segment normally intersecting said chute, there being a slot and a coin engaging shoulder at the rear end of said segment, and a power controlling disk mounted coaxially with said plate and provided with one or more coin slots normally closed by the peripheral segment of said plate.

10. In a coin controlled device, the combination of a coin chute, a detector ledge located adjacent said chute, a power circuit interrupter, a disk in operative relation to said interrupter biased to move in one direction and having a notched periphery intersecting said chute transversely, a rotary plate mounted parallel to said disk and having a peripheral segment normally projecting beyond the notched portions of said disk, and a cam on said plate to disable the operative relation between said disk and said circuit interrupter.

In witness whereof, I have hereunto set my hand this first day of November, 1912.

JOHN T. BEECHLYN.
